UNITED STATES PATENT OFFICE.

KICHINOSUKE HASHIMOTO, OF TOKYO, JAPAN.

FLOATING SHOE.

Application filed July 1, 1924. Serial No. 723,590.

To all whom it may concern:

Be it known that I, KICHINOSUKE HASHIMOTO, a subject of the Emperor of Japan, residing at No. 18 Minami-Igacho, Yotsuya-ku, in the city of Tokyo and Empire of Japan, have invented certain new and useful Improvements in Floating Shoes, of which the following is a specification.

This invention relates to a floating shoe or walking-float which comprises a float inflated with air and provided with depending paddles. An object of the invention is to provide a float shoe of this kind which is adapted to maintain a good stability on water and is capable of being folded up into a small size.

Other objects and advantages will be in part obvious and in part specifically referred to in the specification.

20 In the drawings, illustrating what I now consider the preferred form of my invention,

Fig. 1 is a plan view of the device constructed according to this invention,

25 Fig. 2 is a longitudinal section thereof,

Fig. 3 is a cross section,

Fig. 4 is a detail showing a perspective view of one of the paddles.

Referring now to the drawings, numeral 30 1 indicates a float which is oblong with its both ends pointed. This float 1 is provided at one end with an air valve 2. Upper and lower plates 3, 3 are divided into sections, each section being hinged at 4, so that each plate 3 may be folded when the device is disassembled. Said upper and lower plates 35 3, 3 are attached to the central part of the float 1, on opposite sides, by means of bolts and nuts 5, as shown in the drawings. A 40 shoe plate or foot-rest 6 is hinged at 7 to the middle part of the upper plate 3. Pivots mounted to the lower plate 3 are two or more depending paddles 8, each of which is so arranged that it is permitted to swing 45 about the axis 9 to one direction but is prevented from swinging to the opposite direction.

In operation, air is forced into the float 1 through the valve 2 by means of suitable

air pump, thereby inflating the circumferential part A, B. The walker wears the device, one on each foot, by means of the foot-rest 6, and he walks floating on water. When advance, the paddles 8 come in a position shown in dotted lines, and will not offer considerable resistance to the water. On the other hand, when an attempt is made to force the device back, the paddles 8 will suddenly return to the upright position shown in full lines, and thus the device is prevented from retreat.

It will be seen that by dismounting the paddles 8 and bolts and nuts 5 the device may be folded up into a small size, and consequently that it may be easily carried.

In this device, as before mentioned, the central part of the float 1 is tightened up from both sides by the plates 3, maintaining the surrounding part A, B inflated, and the foot-rest 6 is arranged at the middle part of 70 said plate. Over any heretofore known device, this construction has an advantage that a better stability may be maintained, and consequently it enables the wearer, even an unskilled person, to keep his body stable. 75 Another advantage in this construction lies in that small things if desired may be carried on at the central part, since the device is depressed at said part.

What I claim is:

1. A floating shoe comprising an oblong float provided with upper and lower plates secured to the central part thereof on opposite sides, leaving only the surrounding endless part thereof adapted to be inflated.

2. A floating shoe comprising an oblong float provided with upper and lower plates secured to the central part thereof on opposite sides, leaving only the surrounding endless part thereof adapted to be inflated, and two or more depending paddles which are pivotally mounted to said lower plate in a manner that they swing to one direction but are prevented to swing to the other.

In testimony whereof I have affixed my signature.

KICHINOSUKE HASHIMOTO.
